DESIGN FOR A RADIOCABINET

Robert Himmel, Chicago, Ill.

Application November 13, 1933. Serial No. 49,713

Term of patent 7 years

To all whom it may concern:

Be it known that I, ROBERT HIMMEL, citizen of the United States, residing in the city of Chicago, county of Cook and State of Illinois, have invented a new, original, and ornamental Design for Radiocabinets, of which the following is a specification, reference being had to the accompanying drawings, forming part thereof.

Figure 1 is a front perspective view of radio-

cabinet showing my new design which contains figures of three pigs cut out in the open grille and composed of pressed wood.

Figure 2 shows a side elevational view of the radiocabinet of my design.

I claim:

The ornamental design for a radiocabinet as shown and described.

ROBERT HIMMEL.
